UNITED STATES PATENT OFFICE

GEORGE STEPHENSON WORSSAM, OF WATFORD, ENGLAND, ASSIGNOR OF ONE-HALF TO SAVILLE PERFUMERY LIMITED, OF WATFORD, ENGLAND, A BRITISH COMPANY

BOX OF THE SLIDE-AND-SHELL TYPE

Application filed December 16, 1930, Serial No. 502,717, and in Great Britain February 1, 1930.

This invention comprises improvements in or relating to slide-and-shell boxes of the type having, on the slide, a hinged flap which constitutes a cover for the contents of the 5 slide and is so arranged that when the slide is partially withdrawn from the shell, the flap may be moved about its hinge to uncover the contents of the slide. In one known example of a box of this type, used as a match 10 container, the hinged flap is spring-controlled so that on partial withdrawal of the slide the flap will be automatically sprung into the open position.

The main object of this invention is to 15 adapt a slide-and-shell container of the above type for use as a ladies' vanity box.

According to one feature of the invention the inner surface of the slide flap carries, or 20 is itself arranged to constitute, a mirror. Preferably, as in the known construction previously referred to, the hinged flap is spring-controlled so as to open automatically when the slide is pulled out.

According to another feature of the invention 25 there is fitted within the slide a tray or the like, preferably circular in shape, intended to receive a supply of face powder (e. g. in the form of a compact block) and also if desired to accommodate a small powder puff. Conveniently the tray may be so arranged as to be readily removable from the slide.

In a modified construction according to 30 the invention the slide is spring-urged towards the open position and a catch is provided so that the slide may, when desired, be locked in the closed position with the spring in compression. With this arrangement the 35 slide will open automatically on release of the catch aforesaid.

Two examples embodying the invention will now be described with reference to the 40 accompanying drawing, in which

Figure 1 is a perspective view showing the slide in the open position,

Figure 2 is a similar view with the tray removed,

Figure 3 is a perspective view of the tray 45 itself,

Figure 4 is an end plan view showing the slide only partly withdrawn, and

Figure 5 is a side elevation showing (to some extent diagrammatically) a modified 50 form in which the slide is controlled by a spring.

Like reference numerals indicate like parts throughout the drawing.

Referring in the first place to Figures 1-4 55 the box there illustrated is made of metal throughout and is of flat rectangular shape. The box comprises a shell 10 closed at one end and open at the other, and a slide 11 which is closed at both ends and is fitted with a hinged flap 12 constituting a cover for 60 the major portion of the slide. The hinge 13 of the flap is spaced inwardly a short way from the adjacent inner end of the slide, the arrangement being such that when the slide is pulled out the hinge 13 will be freed before the slide has been completely withdrawn. The underside of the slide is formed with two grooves 14 (Figure 4) with which 65 engage two small tongues 15 struck up inwardly from the underside of the shell. The grooves 14 terminate short of the inner 70 end of the slide, and thus in conjunction with the tongues 15 they provide a stop to prevent the slide being pulled out beyond the aforesaid position in which the hinge is freed.

Associated with the hinge 13 is a spring 75 16 arranged normally to constrain the flap 12 towards the open position in which the contents of the slide are uncovered. The outer end of the slide 10 is formed with a slightly enlarged head piece 17 on the sides of which lugs 18 are formed in order to afford a means whereby the slide may readily be manipulated. The spring 16 associated with the hinge 80 ensures that on partial withdrawal of the slide the flap 12 will be automatically sprung into the open position in which it extends upwardly from the top of the box as shown in Figures 1 and 2. The inner face of the flap 12 is polished so that it constitutes a mirror 85 surface. Between the hinge 16 and the head piece 17 the slide is fitted with a detachable tray 19 in which a circular depression 20 is formed. The outer end of the tray 19 is 90

slipped under the head piece 17, and the opposite end of the tray is sprung into position with the vertical wall of the recessed portion 20 bearing against the wings of a spring 21 which is located at the inner end of the slide by a tab of the hinged spring 16. When the tray is in position, the rim which surrounds the central cavity 20 is substantially flush with the edges of the slide and so presents a neat appearance. The tray is used as a container for powder.

In the second example, illustrated in Figure 5, the slide 11 is urged by a spring 22 towards the open position and a catch 23 is provided so that the slide may, when desired, be locked in the closed position with the spring 22 in compression. With this arrangement the slide will open automatically on release of the catch 23. As will be seen the spring 22 is located between the closed end of the shell 10 and the adjacent inner end of the slide 11. The catch 23 is hinged to the shell and is adapted to be swung up over the mouth thereof (when the slide is closed) and to be sprung over a lip 24. As before the slide is provided with a hinged mirror flap 12 which is spring controlled to open when the slide is pushed out to the position shown in Figure 5. The tray 19 is detachable, and the spring 22 which urges the slide towards the open position is arranged to constitute a means for retaining the tray normally against withdrawal from the slide. As shown, the spring 22 acts on a plunger 25 which in turn presses against the tray.

Various modifications may be made in the constructions described herein without departing from the scope of the invention. For example instead of the flap 12 itself constituting the mirror, a separate mirror may be secured to the flap. The mirror may if desired be furnished by the surface of a circular boss secured to or formed integrally with the flap and arranged to form a counterpart to the cavity 20 in the tray, this arrangement being such that when the flap 12 is closed the boss aforesaid acts to compact the powder in the tray. In a construction of this kind the boss might be arranged to provide a compartment within which a small powder puff could be accommodated. If desired the spring 21 (Figure 2) which holds the tray in position may be located at the opposite end of the slide, i. e. within the head piece 17. With this arrangement the spring (which is held in position by the grip which it exerts on the side walls of the slide) is adapted to engage the vertical wall of the depressed portion 20 of the tray at the outer end of the latter, and the action of the spring is to force the tray towards the hinge end of the slide. At this end of the slide two lugs are formed on the opposite side walls of the slide, and the adjacent end of the tray is forced under

these lugs by the spring 21, and thus held securely in position.

I claim:

1. A vanity box comprising the combination with a slide-and-shell container, of a tray fitted within the slide, a hinged flap articulated to the slide and movable to cover and uncover the contents of the tray aforesaid, a mirror associated with the inner face of the flap, spring means arranged to urge the slide towards the open position and simultaneously to constrain the tray against dislodgment from the slide, and a catch operable at will to lock the slide in the closed position against the action of the spring aforesaid. 70

2. A vanity box comprising the combination with a slide-and-shell container of a tray fitted within the slide, a hinged flap articulated to the slide and movable to cover and uncover the contents of the tray aforesaid, a mirror associated with the inner face of the flap, a helical spring pressing against the inner end face of the slide and arranged to urge the slide towards the open position and simultaneously to constrain the tray against dislodgment from the slide, and a catch operable at will to lock the slide in the closed position against the action of the spring aforesaid. 85

3. A vanity box comprising the combination with a slide-and-shell container, of a tray fitted within the slide, a hinged flap articulated to the slide and movable to cover and uncover the contents of the tray aforesaid, a mirror associated with the inner face of the flap, a helical spring pressing against the inner end of the slide and provided with a plunger at one end which plunger extends through an aperture in the end of the slide and presses against the tray to constrain it against dislodgment of the slide while the spring is arranged to urge the slide towards the open position, and a catch operable at will to lock the slide in the closed position against the action of the spring aforesaid. 100

4. A vanity box comprising the combination with a slide-and-shell container, of a tray fitted within the slide, a hinged metal flap constituting a mirror and articulated to the slide and movable to cover and uncover the contents of the tray aforesaid, spring means arranged to urge the slide towards the open position and simultaneously to constrain the tray against dislodgment from the slide and a catch operable at will to lock the slide in the closed position against the action of the spring aforesaid. 115

5. A vanity box comprising the combination with a slide-and-shell container, of a tray fitted within the slide, a hinged metal flap constituting a mirror and articulated to the slide and movable to cover and uncover the contents of the tray aforesaid, a helical 120

spring pressing against the inner end of the slide and provided with a plunger at one end which plunger extends through an aperture in the end of the slide and presses against the tray to constrain it against dislodgment of the slide while the spring is arranged to urge the slide towards the open position, and a catch operable at will to lock the slide in the closed position against the action of the spring aforesaid.

In testimony whereof I affix my signature.

GEORGE STEPHENSON WORSSAM.
